(57) **CLAIM**

The ornamental design for an epilator, as shown and described.

DESCRIPTION

FIG. 1 is a perspective view of a epilator;
FIG. 2 is a front view thereof;
FIG. 3 is a left side view thereof;
FIG. 4 is a rear view thereof;
FIG. 5 is a right side view thereof;
FIG. 6 is a top plan view thereof;
FIG. 7 is a bottom view thereof.
FIG. 8 is a perspective view of the epilator with a lid thereon;
FIG. 9 is a front view thereof;
FIG. 10 is a left side view thereof;
FIG. 11 is a rear view thereof;
FIG. 12 is a right side view thereof;
FIG. 13 is a top plan view thereof; and,
FIG. 14 is a bottom view thereof.

The epilator is shown with and without the lid for convenience of illustration.
